(57) **CLAIM**

The ornamental design for a truck dump body, as shown and described.

DESCRIPTION

FIG. 1 is a top front perspective view of truck dump body showing my new design;

FIG. 2 is a bottom rear perspective view of the truck dump body illustrated in FIG. 1;

FIG. 3 is a bottom front perspective view of the truck dump body illustrated in FIG. 1;

FIG. 4 is a top rear perspective view of the truck dump body illustrated in FIG. 1;

FIG. 5 is front view of the truck dump body illustrated in FIG. 1;

FIG. 6 is a rear view of the truck dump body illustrated in FIG. 1;

FIG. 7 is a left side view of the truck dump body illustrated in FIG. 1;

FIG. 8 is a right side view of the truck dump body illustrated in FIG. 1;

FIG. 9 is a top view of the truck dump body illustrated in FIG. 1;

FIG. 10 is a bottom view of the truck dump body illustrated in FIG. 1; and,

FIG. 11 is an in use view of the truck dump body illustrated in FIG. 1.

In the drawings, the broken lines depict environmental subject matter only that forms no part of the claimed design.
